RETHREADING TOOL

Roderick Le Bron and William R. Heck,
Omaha, Nebr.

Application March 4, 1946, Serial No. 651,861

2 Claims.

(Cl. 10—1)

1

This invention relates to rethreading tools, and has for its primary object the provision of a simple, rugged and inexpensive tool whereby the threads of various sized pipes and bolts may be readily straightened, cleaned and chased.

Another object of this invention is the arrangement of adjustable thread-cutting and thread-entering guide members on a body portion so that either may quickly be moved as desired by rotating one of two knurled nuts mounted in juxtaposition on the body portion.

A further object of this invention is the provision of a tool that will straighten and reform damaged metal threads and cut them deeper, if desired, as well as remove rust, hardened scale, lead, etc., from the threaded portions of pipes and nuts of various diameters.

Other objects and advantages will be apparent from the following description, taken in connection with the accompanying drawings illustrating a preferred embodiment of our improved rethreading tool, and wherein

Fig. 1 is a side elevation of our improved rethreading tool;

Fig. 2 is a rear elevation thereof;

Fig. 3 is a perspective view thereof; and,

Fig. 4 is a view showing several component elements in elevation.

Referring now to the drawings, the reference numeral 5 designates the body portion of our improved rethreading tool, which body portion is provided with a pair of spaced sockets of different lengths, marked 6 and 7 respectively, and herein shown as extending longitudinally of the body portion 5 in parallel relation. One of the sockets, as 6, terminates adjacent the junction of a pair of guide arms 8 herein shown as arranged at substantially right angles to each other to form a semi-square, with each arm extending at substantially 45° from the upper extremity of socket 6. Guide arms 8 are preferably integrally formed with the body portion 5, substantially as shown, and one arm, as 8A, is joined to the other socket, as 7, whereby a strong, rigid rethreading tool is readily formed with a reinforced body portion capable of being gripped in a vise while pipes or bolts are being turned relatively thereto, or which may be used as a tool handle to rotate the tool around fixed pipes or bolts. One of the guide arms 8 extends laterally beyond the body portion 5 on the side of the shorter socket 6 and is slotted from its free extremity through the major portion of its length, as best shown at 8B in Fig. 3, the slot serving as a guide for the advance and retraction of the cooperating

(Cl. 10—1)

2

pipe or bolt engaging member 9, the bevelled inner edge portions 9A of which are adapted to enter the threads of the pipe or bolt being chased. (Fig. 1.) As herein shown, the bevelled inner edge portions 9A are arranged at substantially right angles to each other to form a semi-square, which is reversely arranged with respect to the semi-square formed by the guide arms 8 of the body portion 5 and cooperates therewith to form a virtual square, adjustable in area and in which the pipe or bolt to be treated is received.

The bolt engaging member 9 is provided at one edge with an elongated threaded post 9C adapted to extend through a suitable aperture 8C (Fig. 3) in guide arm 8A into the longer socket 7 of the body portion and threading into knurled nut 10 arranged in a recess 7A intermediate the ends of the socket. Nut 10 is suitably journaled in socket 7 so that its rotation in the proper direction will serve to advance the bevelled edge portions 9A toward guide arms 8 or retract them therefrom. The opposite edge of member 9 is provided with a depending portion 9B of slightly less width than the width of guide slot 8B wherein it travels as member 9 is advanced or retracted. Member 9 is thereby held against rotation with knurled nut 10, while sufficient side play is permitted to enable bevelled edges 9A to seat within the threads of pipes or bolts being treated despite variations in pitch of threads, pipe diameters, etc. The bevelled edges 9A may also be formed to ride in succeeding threads of pipes and bolts being treated.

A cutter 11 is adjustably mounted in socket 6, extending through an aperture in guide arms 8 adjacent the juncture thereof and having an elongated threaded portion meshing into knurled nut 12 arranged in a recess 6A of the socket. Nut 12 is suitably journaled in socket 6 so that its rotation in the proper direction will serve to either advance or retract the cutter 11 as desired. The cutter edge (or edges) may be formed of hardened metal shaped to correspond with standard pipe threads or, if desire, to deepen the cut and reform the threads in addition to cleaning and chasing the old threads.

In use, the body portion 5 may be suitably secured with the guide arms 8 in substantially the position shown in Fig. 1, and the pipe or bolt to be treated inserted between such guide arms and the cooperating member 9. The position of member 9 is first adjusted to give ample clearance for the pipe or bolt, and the cutter 11 adjusted to approximately its position of use. Then after the pipe or bolt has been positioned with its

threaded portion engaging the cutter 11, the member 9 is drawn down into firm engagement with the upper portion of the pipe or bolt, its bevelled inner edge portions 9A entering the threads so as to aid in maintaining the pipe or bolt in desired position relatively to the cutter 11 while the pipe or bolt is being rotated. The cutter 11 may also have to be adjusted into final position after member 9 has been adjusted, but the adjustment of member 9 alone is often sufficient to force the cutter 11 into the threads to the desired depth.

In some instances it is preferred to clamp the pipe or bolt and revolve the tool around it. The tool is passed over the end of the pipe or bolt, but after bevelled edges 9A of member 9 and the cutter 11 have been suitably positioned within the threads the tool is moved around the pipe or bolt, the body portion being used as a handle. Also the cutter head may be so adjusted relatively to bevelled edges 9A of member 9 as to enter different threads of the pipe or bolt, where by the threads may be cleaned by edges 9A before being recut by cutter 11 or, reversely, marred or deformed portions of threads being recut before such portions contact bevelled edge portions 9A.

It will be obvious that cutter 11 will operate effectively on both right and left hand threads, cleaning, straightening and, where desired, cutting deeper threads leading in either direction. The portion 11A of the cutter between the cutter head and its threaded portion is shaped to cooperate with a similarly shaped aperture in guide arms 8 to prevent rotation of the cutter when knurled nut 12 is rotated. Various polygonal shapes may be employed. To maintain the cutter 11 in any adjusted position, a set screw 13 is provided. (Figs. 1 and 2.)

It will also be apparent that in some instances the guide member 9 may be dispensed with. For example, when a pipe or bolt to be treated is of too great diameter to enter the square formed by guide arms 8 and bevelled edges 9A of member 9, the member 9 may be removed from body portion 5 of the rethreading tool, and the large pipe or bolt allowed to rest upon one guide arm 8 and the cutter head 11. The weight of so massive a pipe or bolt would be sufficient to maintain the cutter head 11 within the grooves of the threads.

From the above it will be apparent that our improved rethreading tool is simple in construction, is composed of few, rugged and inexpensive parts, and is capable of being readily adjusted for use on pipes or bolts of widely varying diameters.

While the illustrated embodiment is believed to sufficiently disclose the construction and ad-

vantages of our rethreading tool, it is to be understood that various changes and modifications may be made therein without departing from the spirit and scope of the invention as defined in the appended claims.

We claim:

1. A rethreading tool comprising a body portion having a pair of sockets of different lengths at its side edges, a pair of guide arms extending laterally and upwardly from the top of the shorter socket, one of said guide arms extending to and forming the upper portion of the longer socket and the other guide arm extending laterally beyond said body portion on the side of the shorter socket, the latter guide arm being slotted from its free upper extremity to a point adjacent said shorter socket, said guide arms being apertured adjacent their junction in alignment with said shorter socket and the first-mentioned guide arm being apertured in alignment with said longer socket, a cutter adjustably mounted in said shorter socket and extending upwardly beyond said guide arms, and a bolt thread engaging member adjustably mounted in and extending above said longer socket and having a depending guide portion extending through said slot in the second-mentioned guide arm, said thread engaging member having angularly disposed bevelled portions adapted to enter the threads of a bolt being chased at spaced points remote from the point of contact of said cutter with such bolt.

2. A rethreading tool as recited in claim 1 wherein both the cutter and the bolt thread engaging member are provided with threaded shank portions extending into their respective sockets, and said body portion is provided with a pair of recesses respectively extending from its sides across said sockets, a knurled nut being arranged in each recess and threaded onto one of said threaded shank portions.
